Inventor:

H. Chamandy
By Egerton R. East
Atty.

UNITED STATES PATENT OFFICE.

HABIB CHAMANDY, OF TORONTO, ONTARIO, CANADA.

WIRE FRAME.

Application filed January 24, 1924. Serial No. 688,212.

To all whom it may concern:

Be it known that I, HABIB CHAMANDY, a subject of the King of Great Britain, of the city of Toronto, county of York, Province of Ontario, Canada, merchant, have invented certain new and useful Improvements in Wire Frames, of which the following is a specification.

My invention relates to improvements in wire frames, and the object of my invention is to design a wire frame that can be used for various purposes, and particularly one that can be used to support price tickets and hold the same attached to a roll of cloth, and thus dispense with the necessity of having to use pins or other fastening devices which are now commonly used and passed into the goods, and in the following specification I shall describe my invention and what I claim as new will be set forth in the claims forming part of this specification.

Fig. 1 illustrates my wire frame. Fig. 2 shows an article, such as a price ticket, carried by the wire frame, and Fig. 3 is an end elevation of the frame.

In the drawings, like characters of reference refer to the same parts.

The article in question is made from a single piece of wire, bent to form two U-shaped sections, A and B, one normally lying within the other. The section A is provided at its inner or upper end according to location with loops C which are coupled together by a tie bar D. The side members E of this section at their lower or outer portions, according to location, are each provided with a loop F. The outer or lower ends of the side members G of the section B are each provided with a loop H, which loops project beyond the loops F, and are integrally formed therewith. Since this frame is made from a single strand of wire, the ends I thereof are suitably twisted together thus fastening the upper or inner ends of the side members G together so as to form a tie bar J. The side members G of the section B are bent to form humps 2 and 3. The humps 3 rest normally more or less in contact with the adjacent portion of their associated side members E, and the humps 2 project beyond these adjacent portions, and the effect of such construction is that if an article be passed between the sections A and B and moved longitudinally thereof, when it passes between said humps

and their associated adjacent portions of the side members E, the article will be yieldingly gripped, and it is this construction that permits the frame to be conveniently attached to a bale of goods, for example, without the necessity of using pins or spurs.

When a card or other article is passed between the sections A and B the loops H will limit its movement longitudinally of said frame.

The price ticket 5 or other article is slightly flexed along the line 6, thus permitting one edge to be slipped underneath the tie bar D, and the other edge to be passed into the loops F. When the card or article 5 springs back to normal shape it will be retained by the loops C and F normally against displacement longitudinally of the wire frame, and this frame with its article or card 5 can be freely handled without disassociation of these elements.

The dotted line 4, in Fig. 2, represents the end of a bolt or a piece of goods, and the article in this figure is supposed to be inserted in the end of said bolt or piece of goods. In order to position the article as described, the said sections are separated at their unconnected ends so that the article may be inserted in said bolt, during which operation, the section A with its ticket 5 will be located above one layer of the piece of goods, and the section B will be located underneath the said layer. Ultimately the edge of the piece of goods will lie in the loops H, which loops limit the distance that the article may be inserted within said bolt.

In Fig. 3 the wire frame is shown on a more or less enlarged scale for the purpose of clearness of illustration, and consequently the hump 3 is shown as spaced apart from its associated portion of the side members E and the loop H is shown opened out.

The tie bar D must be located to overhang the article or card 5.

Although I have mentioned that my wire frame is made from a single strand of wire, this is not to be construed as confining me unnecessarily, because obviously the wire used to make the frame may be composed of several wires twisted together.

From the foregoing part of the specification it will be clear that the frames A and B have a common opening thereinto, which

opening is located between the pairs of loops F and H.

The loops H of necessity are located beyond the loops F, in a direction more or less longitudinally of the article.

The loops C as well as the loops F and H are disposed in planes extending substantially parallel to the plane occupied by the article as a whole.

10 What I claim is:

1. A wire frame made from a single piece of wire bent to form two U-shaped sections disposed longitudinally of each other, and one within the other: one of said sections being provided at one end with a retaining tie-bar which is connected at each end by a loop with the side members of said section, and which section is further provided at its opposite end with loops, the loops at both ends of said section being disposed in substantially a common plane; the other section being provided at its open end with loops projecting outwardly beyond the second-mentioned loops, and lying in a plane substantially parallel to the plane occupied by said second-mentioned loops; said second-mentioned section also being provided

at its outer end with humps which co-act with the side members of said first-mentioned section in the vicinity of said second-mentioned loops, to provide a yielding grip, all of said loops being adapted to permit an article to be passed thereinto and yieldingly grip the same.

2. A wire frame made from a single piece 35 of wire bent to form two U-shaped sections disposed longitudinally of each other, and one within the other: one of said sections being provided at one end with a retaining tie-bar which is connected at each end by a 40 loop with the side members of said section, and which section is further provided at its opposite end with loops, the loops at both ends of said section being disposed in substantially a common plane; the other section being provided at its open end with loops 45 projecting outwardly beyond the second-mentioned loops, and lying in a plane substantially parallel to the plane occupied by said second-mentioned loops, all of said 50 loops being adapted to permit an article to be passed thereinto, and yieldingly grip the same.

HABIB CHAMANDY.
